STOKER APPARATUS

Albert C. Stark, Morton, Pa., assignor, by mesne assignments, to Detroit Stoker Company, a corporation of Michigan

Application September 24, 1952, Serial No. 311,235

4 Claims. (Cl. 110—32)

This invention relates to stokers and control apparatus therefor, and more particularly to temperature-responsive means for controlling the fuel distributing operation of a stoker.

With a spreader stoker comprising a fuel feeding device, a fuel impelling device, such as a fuel throwing rotor, and a fuel receiving grate, to realize maximum combustion efficiency it is desirable that the throw of fuel be neither insufficient nor excessive at or near the wall of the furnace remote from the rotor. Fuel distribution over the grate of such a stoker has heretofore been controlled by manual adjustment of the rotor speed. Under service conditions, however, manual adjustment is uncertain and may be effected too late or cause excessive correction, so that the best combustion efficiency with minimum stack smoke may be obtained only for short periods. As coal size and consist may further vary the distribution as thus effected, undesirable conditions tend to develop, such as loss of attainable combustion efficiency, excessive stack smoke and early deterioration of the refractory wall structure of the furnace.

The temperature at or near the wall remote from the fuel impelling rotor, which may be the rear wall, incident to excessive speed of the rotor of such a stoker, varies considerably from that attained during rotor operation at insufficient speed. It is an object of the present invention to provide means responsive to this temperature variation to control the rotor speed, thereby automatically maintaining the combustion efficiency desired.

Another object of the invention is the provision of stoker control apparatus including a thermocouple pyrometer for indicating relative temperature variations of the fuel bed at or near a wall of a furnace remote from fuel impelling means supplying the fuel bed, a thermocouple pyrometer controller responsive thereto and reversible motor and linkage means controlled by the pyrometer controller for governing the fuel throw effected by the fuel impelling means.

A further object of the invention is the provision of apparatus of the foregoing description for effecting a reduction in speed of a fuel throwing rotor incident to an increase in temperature in a selected combustion zone, and an increase in rotor speed upon a reduction in such temperature.

It is another object to provide stoker apparatus adapted to include interrupting timer means for "inching" the changes in rotor speed, and transfer switch means operable at will to permit manual control of stoker operation under certain conditions, such as during ignition or starting of the furnace.

In order to obviate any adverse effect incident to a change in boiler load on the proper operation of apparatus constructed in accordance with the invention, it has been found desirable to provide means for compensating for transitory variations in furnace temperature, as distinguished from fuel bed temperature. In controlling a furnace in accordance with boiler load, the pressure in the usual primary air duct, through which cool air is delivered to the furnace, is normally maintained at the required value by operation of a suitable damper adjacent the conventional forced-draft fan at the inlet of the primary air duct. This cooling air flow is thus substantially

2

proportional to boiler load. Employing this fact to advantage, it is a further object of the invention to ensure compensation for the above-mentioned boiler load changes by the provision of means for cooling each furnace temperature-responsive thermocouple with air supplied from the primary air duct by way of a restricted passage, the rate of flow of such cooling air being determined partly by the differential between the pressure of air in the duct and the pressure of the furnace atmosphere, and partly by the flow area of the passage.

An additional object of the invention is to provide improved automatic stoker control apparatus having the aforesaid features of temperature-responsive fuel distribution, in which the thermocouple responsive to fuel bed temperature is cooled at high boiler load but not at zero load, so that the resultant compensated response of the thermocouple will remain, at all boiler loads, a useful indication of the fuel bed temperatures substantially uninfluenced by changes in furnace temperature owing to boiler load variations.

These and other objects are effected by the invention as will be apparent from the following description taken in connection with the accompanying drawings, forming a part of this application, in which:

Fig. 1 is a schematic sectional plan view of a stoker equipped furnace having associated therewith a preferred form of temperature-responsive rotor control apparatus constructed and arranged in accordance with the invention;

Fig. 2 is a sectional elevational view of a portion of the apparatus shown in Fig. 1; and

Fig. 3 is a fragmentary enlarged detail sectional view of one of the cooling air compensated thermocouples of the apparatus shown in Fig. 1.

Referring to Fig. 2, a typical power plant installation, as shown in elementary form, may comprise opposed walls such as front and rear furnace walls 10 and 11 serving with suitable side walls to enclose a boiler structure 12 and a combustion chamber 13. Stoker apparatus is provided comprising a traveling chain grate 14 for supporting a fuel bed, indicated by the reference character 15 over which coal or similar fuel is distributed from a hopper 16 by operation of one or more rotors 17 that are rotatably mounted in a housing 18 carried by the front wall 10. Any other type of fuel distributing or impelling means may be substituted for the rotors 17, if preferred. In the form shown, it will be understood that fuel will be distributed at a rate dependent upon the speed of the rotors 17. Wind box compartments 19 and 20 are suspended from a frame 21 beneath the chain grate 14, and are adapted to be supplied with air under pressure from a suitable fan (not shown) by way of ducts, such as an air duct 22.

As shown diagrammatically in Fig. 1, the rotors 17 are adapted to be driven at selected variable speed by a hydraulic motivating system including a motor 24, which is operative by fluid supplied through a pipe system 25 from a reservoir 26 by a pump 27, under the control of suitable hydraulic control apparatus 28, as disclosed in greater detail, for example, in Patent No. 2,603,421, issued to D. J. Mosshart on July 15, 1952, and assigned to the assignee of the present invention.

This hydraulic motivating system is further controlled, according to the present invention, by means of an electro-responsive speed control valve device 30 operable by a reversible motor 31, which is energized in accordance with the suitably amplified energy output of a thermocouple pyrometer control device 32. The structural details of the thermocouple pyrometer controller 32 are not disclosed, since such details are unnecessary for a full understanding of this invention, but it will be understood that this device may be of any well-known construction suitable for actuating the rotor speed control valve

device 30 in response to the temperature indications of one or more thermocouples 34, which are disposed adjacent the furnace wall remote from the fuel impelling device or rotors, in this case the rear wall 11 of the furnace structure, for measuring the local temperature of the fuel bed 15. A suitable control circuit 35 is provided for connecting the thermocouples in series to the thermocouple pyrometer controller 32.

As best shown in Fig. 3, each thermocouple 34 is mounted in a shield or tube 37 having an end opening 38, the tube extending through the side wall 11a at an angle α with the end opening directed toward the fuel bed 15 at or near the rear furnace wall 11. Each of the tubes 37 has a passage 38a which communicates by way of a restricted passage or orifice 39 and a conduit 40 with an air receiving probe member 42, which extends into the air duct 22 with the open end 42a of the probe member directed upstream. Sufficient space is left around each thermocouple 34 to allow flow of cooling air through the passage 38a and opening 38. Each thermocouple 34 may readily be adjusted relative to the protecting tube 37 containing it to provide any desired scanning range or angle of survey A of the fuel bed 15, corresponding to the angle of inclination of the tube.

Suitable interrupting timer means for "inching" the changes in rotor speed, and transfer or changeover means operable to permit manual control of the rotor speed when desired, may be included in the control apparatus 28. Such means are well known, and detailed disclosure thereof is consequently not deemed necessary.

From the foregoing it will thus be seen that, with an improved stoker control system embodying the invention, the relative temperature of the fuel bed at or near the rear wall of the furnace, as indicated by the thermocouples 34 is measured for effecting operation of the thermocouple pyrometer controller 32 for actuating a reversible motor with suitable linkage and valve means to govern the speed of the fuel throwing rotors 17, so that the latter will be driven at a slow rate in response to a temperature higher than a selected control temperature, or at a relatively fast rate in response to a lower temperature. The improved control system further ensures compensation for changes in boiler load, in order to prevent such changes from adversely affecting the distribution of fuel called for by the temperature of the fuel bed, by cooling the thermocouples 34 with air taken from the primary air duct 22, the quantity of cooling air being determined by the difference between pressure of air in the duct and that of the furnace atmosphere, with relation to the flow areas of the restricted passages or orifices 39 in the air supply pipe 40. Since the pressure of air maintained in the primary air duct 22 is normally that required for the boiler load, as controlled by a damper (not shown) in cooperation with the usual forced-draft fan (not shown) supplying air to the duct, this cooling air flow is proportional to the boiler load. With this compensation, each thermocouple is cooled at high boiler load, with no cooling at zero load, so that the resultant response of the thermocouple is a substantially accurate indication of the fuel bed temperature with minimum error incident to any change in furnace temperature owing to load variation. The stoker control apparatus, in operation in response to the fuel bed temperature indications of the thermocouples, thus will maintain the desired fuel distribution at all boiler loads.

While the invention has been shown in but one form, it will be obvious to those skilled in the art that it is not so limited, but is susceptible of various changes and modifications without departing from the spirit thereof.

What is claimed is:

1. In stoker control apparatus for a boiler furnace equipped with a primary air duct through which air is supplied at a high rate when boiler load is high and at a lower rate when boiler load is low, said furnace having a grate for supporting the fuel bed, a motor-driven fuel

throwing rotor, control means for controlling the speed of said rotor, electro-responsive thermocouple pyrometer control means for actuating said control means, a control circuit for energizing said thermocouple pyrometer control means, thermocouple means disposed in heat-responsive relation to the fuel bed on said grate for effecting energization of said circuit, and conduit means communicating with said air duct and with said thermocouple means for supplying cooling air from said air duct to said thermocouple means to compensate said thermocouple means for changes in temperature of the furnace atmosphere incident to changes in boiler load.

2. In stoker control apparatus for a boiler furnace equipped with a primary air duct through which air is supplied at a high rate when boiler load is high and at a lower rate when boiler load is low, said furnace having opposite first and second walls and a grate supporting the fuel bed, a fuel throwing rotor operative near said first wall to distribute fuel over said grate, motor means drivingly connected to said rotor, speed control means for varying the speed of said motor in accordance with fuel requirements of the furnace, electro-responsive thermocouple pyrometer control means operative to adjust said speed control means, a control circuit for energizing said

thermocouple pyrometer control means, thermocouple means disposed near said second wall of the furnace in heat-responsive relation to a local area of the fuel bed for effecting energization of said circuit in accordance with fuel bed temperature, and conduit means communicating with said air duct and with said thermocouple means for supplying cooling air from said air duct to said thermocouple means to compensate said thermocouple means for changes in temperature of the furnace atmosphere incident to changes in boiler load.

3. In stoker control apparatus for a boiler furnace equipped with a primary air duct through which air is supplied at a high rate when boiler load is high and at a lower rate when boiler load is low, said furnace having opposed first and second walls and a grate for supporting the fuel bed, in combination, a fuel throwing rotor mounted in the first wall of the furnace and operative to distribute fuel over said grate, motor means for driving said rotor at selected speeds in accordance with fuel requirements of the furnace, speed control means operable for controlling the operation of said motor means, electro-responsive thermocouple pyrometer control means for operating said speed control means, a control circuit for energizing said relay means, a hollow shield mounted in said furnace near the second wall remote from said rotor and having an open end directed toward the fuel bed supported by said grate, a thermocouple mounted in said shield with clearance forming a flow passage, said thermocouple being disposed in heat-responsive relation to the fuel bed and connected to said control circuit, and a conduit communicating with said air duct and with the flow passage in said shield for supplying cooling air to compensate said thermocouple for changes in temperature of the furnace atmosphere incident to changes in boiler load.

4. Apparatus as set forth in claim 3 wherein an orifice is interposed in said conduit for controlling the flow of cooling air to said thermocouple.
